Figure 1. A schematic diagram of the experimental setup. The sample is a rectangular block of $10 \times 10 \times 10$ mm³ with a central cavity of $5 \times 5 \times 5$ mm³. The sample is placed on a rotating stage, which is mounted on a vibration isolator. The stage is illuminated by a laser beam, and the reflected light is collected by a lens and focused onto a photodetector. The photodetector is connected to a lock-in amplifier, which is synchronized with the rotation of the stage. The rotation of the stage is controlled by a motor, which is driven by a power supply. The power supply is connected to a computer, which controls the rotation of the stage and the acquisition of data.

DISTILLATION OF TAR

Arthur H. Radasch, Bloomfield, N. J., assignor to
The Barrett Company, New York, N. Y., a cor-
poration of New Jersey

Application July 8, 1931, Serial No. 549,419
Renewed January 27, 1936

8 Claims. (Cl. 260—154)

This invention relates to the distillation of tar and includes both the process and apparatus therefor. More particularly the invention relates to a novel method of recovering tar acids from tar.

It is customary to recover the tar acids from tar by distilling the tar, obtaining a distillate and extracting the condensed distillate or a fraction of the condensed distillate with caustic soda or other alkaline reagent. This necessitates large tanks for the storage of tar-acid oil and extensive equipment for the liquid extraction. The present method does not require such storage facilities and does provide a continuous process by which the tar acids are recovered from the vapor phase in conjunction with the tar distillation.

There are many advantages in vapor phase extraction of the tar acids as compared with extraction in the liquid phase. By vapor phase extraction I refer to bringing the tar-acid vapors in admixture with vapors of non-acid or neutral oils into contact with an alkaline reagent whereby salts of the tar acids are formed and the tar acids are thus recovered and separated from non-acid constituents without first condensing them. In order to extract tar acids in the vapor phase without condensing oils the extraction must be carried out without any substantial cooling of the vapors. In order that the extraction may be effected with an aqueous solution it is advantageous that the vapors extracted shall not be so hot as to evaporate an excessive amount of water from the solution because such evaporation will cause crystallization or solidification of the solute from the solution and will cool the vapors and cause condensation. Commercial solutions containing about 47 to 50% of caustic can be used in extracting gases or vapors at temperatures up to 200° C. or somewhat higher, without the evaporation of excessive amounts of water.

The temperature of the vapors resulting from distilling the tar may be so high that vapor phase extraction of these vapors is not practicable. According to this invention, therefore, the vapors are cooled in a heavy oil condenser to a temperature at which they can be extracted with an aqueous solution of an alkaline reagent. Higher boiling oils, including the higher boiling tar acids, are condensed in the cooling process while the lower boiling oils including lower boiling tar acids remain in vapor form. Tar acids are distilled from the condensed heavy oil by passing a large volume of tar-acid-free inert gases through the heavy oil. The gases and vapors from this inert

gas distillation are blended with at least a part of the vapors of the lower boiling tar acids and neutral oils that are not condensed with the heavy oil. The blended gases are then extracted with an aqueous solution of caustic or other alkaline reagent, which removes tar acids as carbolate and the carbolate so formed includes tar acids that are vaporized from the heavy oil condensate and also tar acids that are not condensed with the heavy oil but remain as vapors after condensing the higher boiling oils. Tar acids are thus separated from vapors of non-acid constituents. It is advantageous to recycle at least a portion of the resulting vapors through the heavy oil condensate to aid in the distillation of tar acids from the heavy oil condensate. The tar-acid distillation is then selective in so far as vapors of neutral oils in the recycled gases and vapors prevent or inhibit distillation of neutral oils from the heavy oil condensate.

In this distillation of tar acids from the heavy oil condensate, inert gases such as steam may be employed, and at least in part recirculated. According to a preferred method, however, the recirculated gases include vapors of non-acid constituents present in the heavy oil or in the non-condensed vapors from the heavy oil condenser. "Gases" is used in this application in a broad sense to include non-condensable gases such as nitrogen, etc., which may be employed in the inert gas distillation, and condensable vapors such as steam and vapors of neutral oils.

If desirable, a condenser may be employed in the cycle before the gases enter the caustic tower and the condenser may be placed in such a position that it acts upon the recycled gases before or after the vapors from the distillation of the heavy oil are blended with the lower boiling vapors from the heavy oil condenser; or a condenser may be included in the cycle for cooling the vapors after they leave the caustic extractor. If the condenser precedes the caustic extractor, tar-acid oils are condensed. If the condenser follows the caustic extractor, the oils may be neutral oils or oils of at least relatively low tar-acid content.

It may be desirable to treat separately the vapors from the heavy oil condensate with caustic or other alkaline reagent to recover the tar acids present in this heavy oil condensate before blending these vapors with the vapors leaving the heavy oil condenser. Further, it may be desirable to insert a condenser in this inert gas cycle after such a caustic extractor to condense separately neutral oils distilled from the heavy oil condensate before blending the vapors from the distilla-

tion of this heavy oil condensate with the vapors leaving the heavy oil condenser.

Various modifications of the process are possible within the scope of this invention. By condensing and drawing off the heavy oil fraction without excessive cooling, condensate is obtained which generally contains sufficient heat to effect the inert gas distillation of tar acids from the oil without other heating. Thus the entire heat required for the distillation of tar acids from the heavy oil condensate may be supplied to the tar in the still. Additional heat may be supplied to the system to effect the distillation of tar acids, if necessary or desirable, as, for example, by heating the oil by heat interchange with steam or other heating medium before or during the inert gas distillation, or by heating the circulated gases, etc. According to the preferred method, however, the tar acids are vaporized by the self-contained heat of the heavy oil condensate.

The rate at which the inert gases are circulated through the hot condensate is correlated with the temperature of the condensate so that the desired percentage of the tar acids is vaporized from the condensate. By limited distillation, lower boiling tar acids can be obtained, such as a mixture of phenol and the cresols which contains a relatively small amount of the higher boiling acids. By repeated fractional treatments desired tar-acid fractions can be obtained from the same condensate.

The vapors from the tar distillation may be at such high temperature that one or more separate heavy oil fractions may be condensed before condensing a tar-acid oil fraction containing desired tar acids.

The process is applicable to the treatment of tars, such as coke-oven tars, gas-retort tars, vertical-retort tars and low-temperature tars and other tar-acid and neutral-oil-containing hydrocarbon materials such as coal-tar oils. It may be applied to the treatment of raw, moisture-containing tar or stripped tar, etc., or to the separate treatment of tar fractions such as the heavy tar from the collector main of a coke-oven plant, or the light tar or tarry oil from the condensers of such a plant. It may be applied to the treatment of mixtures containing coal tar, etc. The invention will be described more particularly as applied to the treatment of coke-oven tar.

In the vapor phase extraction of tar acids, caustic soda has proven very satisfactory, and because of its relative cheapness it is considered a desirable alkaline reagent for use in this connection. Other neutralizing agents may be employed.

It is advantageous to carry out the tar distillation process as a continuous process in which the vapors leave the still at a substantially uniform temperature although the invention may also be applied to a batch distillation process. When the tar is continuously distilled a pipe still is preferred for this purpose although a tank still or pot still can be employed. A series of stills arranged, for example, on the cascade principle, may be employed. The heavy oil condenser employed may be used in conjunction with an ordinary fractionating column. Selected oil fractions from the condensing or fractionating units may be treated for the recovery of graded tar acid fractions.

The tar-acid still in which tar acids are distilled from the heavy oil condensate may be a

packed tower or a grid tower of the type employed for bringing a gas and liquid into intimate contact, or any other suitable gas and liquid contact apparatus may be used.

The caustic extractors may likewise be packed towers or grid towers or other apparatus containing suitable spray means. Preferably the caustic extractors include more than one contact chamber in each of which the gases are sprayed with caustic for efficiency in removal of tar acid vapors from other vapors. In order to provide contact between a large surface of the caustic and the vapors it is advisable to recirculate, with the fresh caustic employed, a part of the carbamate already formed. By providing two or more chambers for the extraction it is possible to admit fresh caustic to one, recirculate the carbamate formed in it and withdraw carbamate produced in the final chamber, as described in connection with the drawings, without withdrawing any large percentage of uncombined caustic with this finished carbamate.

After the extraction of tar acids from the vapors from the heavy oil condensation, the vapors may be further cooled and oils condensed either fractionally or to produce a total condensate. These oils will be relatively free from tar acids, depending upon the thoroughness with which tar acids are removed from the vapors during the tar acid extraction. They will include lower boiling oils distilled from the heavy oil condensate.

The character of the pitch produced will depend upon the type of tar treated, the temperature to which the tar is heated in the still and the amount of oil removed from it. If oils are distilled the residue from the distillation will be a heavy oil although in some cases it will be a pitch. The invention will be further described in connection with the accompanying drawings but it is intended and is to be understood that it is not limited thereto.

Fig. 1 shows a tar still which includes a heating coil and vapor box connected with a fractionating column especially equipped for the recovery of tar acids;

Figs. 2 to 6 are modified forms of the apparatus shown in Fig. 1;

Fig. 7 shows apparatus which may be employed in connection with a simple still to carry out the invention; and

Fig. 8 shows a series of simple stills arranged for continuous distillation.

In the drawings the same numeral is employed to indicate like apparatus with the addition of a distinguishing letter for each different figure.

According to the arrangement of Fig. 1, the tar to be treated is heated in the coil 1 of the pipe still and then flashed in the vapor box 2. The vapors are separated from residue which is drawn off into the pitch receiver 3. The vapors pass through the main 4 to the section 5 of the fractionating column. Other sections of the fractionating column are shown at 6 and 7. Between the column sections are cooling coils 8, 8' and 8''.

A heavy oil fraction is removed from section 5 by cooling the vapors to a temperature such that the oils condensed contain a negligible amount of tar acids of commercial value. On further cooling oils will be condensed which will contain desirable tar acids. From section 6 an oil is withdrawn which contains a part of the desired tar acids and the balance of the desired tar acids pass in vapor form through the main 9 to the caustic extractor 10. There is no gas or liquid passage between the cooling coils 8' (above sec-

tion 6) and section 7 of the column. All of the vapors pass from the cooling section above section 6 through the main 9 to the caustic extractor 10 and vapors pass from the caustic extractor 10 back to section 7 through the main 10'. The vapors enter section 6 at a temperature above that at which they can be extracted in the vapor phase by caustic. They are cooled by the cooling coils above section 6 to about 200° C. or lower and 10 are passed to the caustic tower 19 at this temperature.

The oil withdrawn from the section 6 through the line 6' enters the tar-acid still 12, which is shown as a packed tower in which the oil is 15 brought into intimate contact with inert gases circulated through the line 11 by the blower 11'. These inert gases cause distillation of tar acids from the oil. The tar acids and inert gases pass from the tower 12 through the main 13 and are 20 combined with the vapors leaving the cooler 8' of the column and are together treated in the caustic extractor 10. In the caustic extractor tar acids are extracted from the vapors and separated as carbolates. If the extraction of tar acids is 25 thorough, the oil obtained by cooling the vapors following such extraction will be a neutral oil.

A part of the gases from the caustic tower are recirculated through the tower 12. These gases are relatively free from vapors of tar acids, but 30 contain neutral oils which repress further distillation of neutral oils from the heavy oil in the tar-acid still 12, but do not interfere with vaporization of tar acids. The residue drawn off from the tower 12 and collected in the tank 14 will be 35 a neutral oil or oil of relatively low tar-acid content.

The caustic extractor shown is of a preferred type. Fresh caustic is introduced at 15. The extractor is divided into two sections, each of which 40 preferably contains grids or other means for exposing a large surface of liquid to the gases passing through it. In connection with each section a line 16 is provided for withdrawing carbolate which is pumped by pumps 17 through the heat 45 interchangers 18 and sprayed into the gases through the spray nozzles 19. Finished carbolate is drawn off through the line 20 into the receiver 21. The temperatures of the sprayed solutions are preferably so controlled by the heat interchangers 18 that there is substantially no condensation of oils in the caustic extractor. If desired, the vapors may be cooled to effect condensation of neutral oils in the caustic extractor.

As an example of a method of operating the apparatus shown in Fig. 1, it is possible to heat coke-oven tar of about 3% tar-acid content in the coil 1 to a temperature of 400° C. On flashing, the vapors leave the vapor box 2 through the main 4 at a temperature of about 380° C. and pitch with 50 a melting point of about 210° F. is produced. The vapors are cooled in passing through the section 5 to a temperature of about 280° C., and the oil drawn off of the section 5 through the outlet 5' has a boiling range of about 248° C. to over 400° C. In the section 6 the vapors are cooled to 200° C. This yields a heavy oil condensate which is drawn off to the tower 12. The uncondensed vapors pass through the main 9 at a temperature of about 200° C. to the caustic tower.

The oil drawn off into the tower may represent 70 about 15% of the tar treated and contains, for example, 20% or more of the tar acids in the tar. This oil has a temperature of about 250° C. By recirculating the inert gases through this oil at a rate of 150 cubic feet per gallon of oil treated it

is possible to recover in the neighborhood of 80 to 90% of the tar acids in the oil.

After extracting the tar acids the vapors are in part returned to the fractionating column through the line 10', and the balance are recycled 5 through the tar-acid still 12 through the line 11. By the cooling coils 8'' above section 7 of the fractionating column the vapors are further cooled and a neutral oil of lower boiling range is obtained. The vapors are subsequently totally 10 condensed in the final condenser 7'. Instead of the fractionating column 7, as shown in Fig. 1, the vapors leaving the caustic extractor may pass directly to the final condenser 7' and be totally 15 condensed.

In Fig. 2 the vapors pass directly from the vapor box 2a to the condenser 6a from which the heavy oil condensate is drawn off to the tar-acid still 12a. The omission of any condenser corresponding to the section 5 and cooling coils 8 of 20 Fig. 1 is possible if the tar is distilled to lower melting point pitches. It may even be desirable if high melting point pitch is made, collecting the higher-boiling oils together with intermediate boiling tar-acid-containing oils and drawing both 25 off together into the tar-acid still. This gives a larger bulk of oil to be treated in the tar-acid still, but the extra sensible heat content of the higher-boiling oils may at times be an aid to the inert gas distillation. The condenser 6a may be 30 an indirect condenser in which water or other cooling fluid is circulated through tubes; or part of the condensate may be cooled and recirculated; or any other suitable type of condenser may be used. In Fig. 2 simple condensers are shown for 35 simplicity, and the caustic extractor is shown for simplicity as a single packed tower 10a instead of the preferred extractor shown at 10 in Fig. 1.

The apparatus of Fig. 3 includes a condenser 22 between the caustic tower 10b and the tar- 40 acid still 12b. In the apparatus of Fig. 1 there is no direct gas passage between the sections 6 and 7 of the fractionating column. All of the gases from the section 6 pass through the main 9 to the caustic extractor. In Fig. 3 there is an 45 open passage between the sections 6b and 7b of the fractionating column. The main 9b connects with the caustic tower and the inert gas cycle is maintained under equalized pressure by a portion of the vapors passing from the fractionating 50 column into the caustic extractor 10b through this connecting main. The gases and vapors from the tar-acid still 12b combine with these vapors from the fractionating column and the combined 55 gases and vapors pass to the caustic tower 10b where they are extracted to recover tar acids. The resulting vapors pass to the condenser 22. In this condenser a neutral oil or oil of relatively 60 low tar-acid content is condensed, depending upon the extent to which tar acids are extracted and removed in the extractor 10b. The cooling in the condenser 22 can be so regulated as to produce an oil of desired boiling range.

An arrangement similar to Fig. 3 is one in 65 which the condenser is placed before the caustic extractor. The vapors from the fractionating column may blend with the gases and vapors from the still 12b, either before or after passing through the condenser.

In Fig. 4 a condenser 23 is included in the inert 70 gas cycle preceding the caustic tower 10c. Vapors from the tar-acid still 12c are cooled in the condenser 23 and a portion of the vapors condensed and recovered as tar-acid oil in this condenser 75

before the vapors pass on to the caustic extractor. The cooling in the condenser 23 may be so regulated as to produce an oil of desired boiling range. A modification of the arrangement shown in the drawing is one in which the gases and vapors from the still 12c combine with the vapors from the column before they enter the condenser 23.

When operating according to Figs. 3 and 4 it is not necessary that the vapors leaving section 6b and section 6c be cooled to 200° C., since the vapors will be combined with the cooler gas of the inert gas cycle. It is sufficient that the combined gas stream be about 200° C. or lower before being brought into the extractor. The temperature of the vapors leaving the column through the mains 9b and 9c and the temperature of the circulating inert gases are regulated according to the respective amounts of each to give the proper operating temperature within the caustic extractors 10b and 10c.

The oils withdrawn from section 6d of the fractionating column shown in Fig. 5 are oils of higher boiling range than those which pass in vapor form to the caustic tower 10d through the main 9d. It may therefore be desirable to extract tar acids separately from this higher boiling oil before blending vapors from the inert gas distillation in the tar-acid still 12d with vapors from the section 6d. A caustic tower 24 is therefore provided for separately treating these vapors. Caustic is sprayed into the tower 24 in order to recover the higher boiling tar acids before blending vapors from the still 12d with the vapors from the section 6d of the fractionating column. By thus separately recovering higher boiling tar acids the phenol content of the tar acids recovered in the caustic tower 10d may be increased.

The apparatus of Fig. 6 is somewhat similar to that shown in Fig. 5 but in addition to the caustic tower 24e for extracting higher boiling tar acids, a condenser 25 is shown for fractional condensation of neutral oils in the inert gas cycle before the vapors distilled in the tower 12e enter the caustic tower 10e. By careful regulation of the cooling in the condenser 25, an oil of relatively low tar acid content is thus separately collected. The temperature of the gas leaving the condenser 25 and the temperature of the gas passing from the column through the main 9e are each regulated so that the temperature of the continuous gases is not above about 200° C.

A fractionating column with condensers, or simple condensers can be employed in any of the modifications shown, as desired. In the apparatus of Fig. 3 there is open communication between the sections 6b and 7b of the fractionating column. In the apparatus of Figs. 1, 2 and 4 to 6 the gases from the sections 6, 6a, etc., when passing to the section 7, 7a, etc., must first pass through the caustic tower 10, 10a, etc.

Fig. 7 shows an arrangement for the continuous distillation of tar and production of pitch in a simple, direct-fired still 26. The arrangement is intended for use in connection with a process in which high melting point pitch is produced. The gases pass from the still through the condensers 5f, 6f, 7f and 28 and the condensation is so controlled that the heaviest oil condensed in 5f contains no appreciable amount of desired tar acids. The oils from the condensers 6f and 7f are tar-acid-containing oils. They are drawn off into the tar-acid still 12f. The vapors from the still are cooled in these condensers so that they leave the condenser 7f at a temperature in the neighbor-

hood of 200° C., and the vapors leaving this condenser still contain tar acids. These vapors combine with the gases and vapors from the tar acid still 12f and pass through the extractor 10f. A portion of the extracted gases and vapors is recirculated through the tar acid still 12f. The balance passes to the condenser 28, in which, on further cooling, an oil fraction substantially free from tar acids is obtained. This oil fraction generally will contain 2% or less of tar acids depending upon the extent to which tar acids are removed in the caustic extractor 10b.

In Fig. 8 a cascade of stills is shown connected with condensers and a caustic extractor for carrying out this invention. The tar enters the still 30 and after partial distillation flows in series through the stills 31, 32 and 33 and is progressively distilled as it passes through the stills.

The lightest oils are vaporized in the still 30 and higher boiling oils are progressively distilled from the stills 31, 32 and 33. The highest boiling oils from the still 33 pass through the condenser 35 and are subjected to fractional condensation therein. The residual vapors combine with the vapors from the still 32 and pass through the condenser 36. Similarly, the residual vapors from condenser 36 combine with the vapors from still 31 before passing to the condenser 37. The residual vapors from the condenser 37 combine with the vapors from the still 30. In an ordinary distillation they pass directly to the worm condenser 34 but when tar acids are recovered they are passed through the caustic extractor 10g before passing to the condenser 34.

The cooling in the condenser 35 is so regulated that the oil fraction condensed therein contains no considerable amount of tar acids. The condensate from the condenser 37 and generally also the condensate from the condenser 36 contain tar acids. These condensates run into or are pumped by the pump 39 into the tar-acid still 12g in which tar acids are distilled from the oils by a current of inert gases. The gases and vapors from the tar acid still 12g are blended with the vapors from condenser 37 and from still 30 and are then passed through the caustic extractor 10g. The cooling in condenser 37 is so regulated that the combined vapors entering the caustic extractor 10g are at a temperature in the neighborhood of 200° C. or lower and can therefore be extracted directly with caustic soda. Part of the extracted vapors are recirculated and again passed through the tar acid still 12g. The balance of the extracted vapors passes through the worm condenser 34.

Instead of the single condensers arranged in series shown in Figs. 7 and 8, a fractionating column may be employed. In each of the arrangements shown a caustic tower such as that shown in Fig. 1 is to be preferred for the extraction of the vapors.

The invention is not limited to the arrangements shown in the drawings or to the specific processes described. It is defined in the appended claims.

I claim:

1. The method of treating tar-acid and neutral-oil-containing hydrocarbon material, which comprises distilling the material, cooling the vapors to condense part but not all of the tar acids thereby producing a tar-acid-containing condensate, vaporizing tar acids from this condensate, blending the tar acid vapors with uncondensed vapors resulting from the distillation of 75

the hydrocarbon material and extracting the blended vapors for tar acids by contact with an alkaline reagent.

2. The method of treating tar-acid and neutral-oil-containing hydrocarbon material, which comprises distilling the material, cooling the vapors to condense part but not all of the tar acids thereby producing a tar-acid-containing condensate, vaporizing tar acids from this condensate, blending the tar acid vapors with uncondensed vapors resulting from the distillation of the hydrocarbon material and extracting the blended vapors for tar acids by contact with an alkaline reagent, the vaporization of the tar acids being effected by the self-contained heat of the condensate.

3. The method of treating tar-acid and neutral-oil-containing hydrocarbon material, which comprises distilling the material, cooling the vapors to condense part but not all of the tar acid vapors thereby producing a tar-acid-containing condensate, vaporizing tar acid from the condensate while still hot in a current of inert gases containing neutral oil vapors, blending the resulting gases and vapors with uncondensed vapors resulting from the distillation of the hydrocarbon material, extracting the blended vapors for tar acids by contact with an alkaline reagent and recycling at least a portion of the resulting gases and vapors to aid in the vaporization of the tar acids from the condensate.

4. The method of obtaining tar acids from tar, which comprises distilling the tar, cooling the distillate vapors to condense part but not all of the tar acids therefrom, thereby producing a tar-acid-containing condensate, vaporizing tar acids from this condensate while still hot, extracting part but not all of the tar acids therefrom by contact with an alkaline reagent, blending the resulting tar acid vapors with uncondensed va-

pors from the distillation of the tar and extracting tar acids therefrom by contact with an alkaline reagent.

5. The method of treating coke oven tar, which comprises heating the tar to a temperature of at least 250° C., flashing the heated tar, cooling the vapors from the flashing operation to a temperature not above 210° C., thereby producing a tar acid oil, vaporizing tar acids from this oil, blending at least a portion of the tar acid vapors with uncondensed vapors from the flashing operation, and extracting the combined vapors by bringing an alkaline reagent into contact therewith.

6. The method of recovering tar acids, which comprises subjecting tar to distillation, cooling resulting vapors to condense a tar acid oil while leaving part of the tar acids in vapor form, vaporizing tar acids from the tar acid oil and blending them with the tar-acid-containing vapors, and then extracting the blended vapors by contact with an alkaline reagent.

7. The method of recovering tar acids, which comprises distilling tar to pitch, cooling the vapors to a temperature not above 200° C., thereby producing a tar acid oil while leaving tar acids in the vapor state, vaporizing tar acids from this oil, blending at least a portion of these vapors with uncondensed vapors from the distilling operation and extracting the combined vapors by contact with an alkaline reagent.

8. The method of recovering tar acids, which comprises progressively distilling tar in a series of stills, condensing a tar-acid-containing oil from the vapors from one of the stills, vaporizing tar acids from this oil, blending these vapors with tar-acid-containing vapors from one of the other stills and extracting tar acids from the blended vapors by bringing an alkaline reagent into contact therewith.

ARTHUR H. RADASCH. 40
